UNITED STATES PATENT OFFICE

145,237

DESIGN FOR A COMBINATION RADIO AND PHONOGRAPH CABINET

Cecil Barre Thorne, New York, N. Y.

Application August 25, 1945, Serial No. 121,627

Term of patent 14 years

(Cl. D56—4)

To all whom it may concern:

Be it known that I, Cecil Barre Thorne, a citizen of the United States, residing at New York, in the county of New York and State of New York, have invented a new, original, and ornamental Design for a Combination Radio and Phonograph Cabinet, of which the following is a specification, reference being had to the accompanying drawing, forming part thereof.

Figure 1 is a front perspective view of a combination radio and phonograph cabinet showing my new design, and

Figure 2 is a top plan view thereof.

The characteristic features of my design are shown by means of full lines in the drawing.

The rear elevational surfaces of my design are plain and unornamented.

I claim:

The ornamental design for a combination radio and phonograph cabinet, as shown and described.

CECIL BARRE THORNE.
